UNITED STATES PATENT OFFICE.

ADDISON G. WATERHOUSE, OF NEW YORK, N. Y., ASSIGNOR TO THE UNITED STATES ELECTRIC LIGHTING COMPANY, OF SAME PLACE.

CARBON-HOLDER FOR ELECTRIC LAMPS.

SPECIFICATION forming part of Letters Patent No. 252,404, dated January 17, 1882.

Application filed April 30, 1881. (No model.)

To all whom it may concern:

Be it known that I, ADDISON G. WATERHOUSE, a citizen of the United States, residing in New York, in the county of New York and State of New York, have invented certain new and useful Improvements in Carbon-Holders for Electric Lamps, of which the following is a specification.

My invention relates to the devices employed in electric-arc lamps for holding the carbons in position, and its objects are, mainly, to so construct these holders that they shall be easily detached from the lamp-frame, readily adjusted for the various angles or vertical lines in which it is necessary to place the carbon pencils, and shall secure a perfect electrical contact between the metal of the lamp and the pencil. These ends I attain by the devices illustrated in the accompanying drawings, in which—

Figure 1 is a view of the upper holder; Fig. 2, a part sectional view of the lower holder, showing the same attached to the lower cross-piece of a lamp; Fig. 3, a plan view of the upper part of the holder; Fig. 4, a view of the clamping devices detached, and Fig. 5 a modification of the same.

The letter A in Fig. 1 represents a portion of the upper carbon-carrier provided, as shown in dotted lines, with a ball on its end. To this the carbon-holder, consisting of the two clamps d and b and binding-screw S, is attached. The two parts d and b of the holder are cut or molded in such shape on their interior surfaces that when brought together by the screw S their upper ends will inclose the ball B and their lower portions tightly embrace the end of a carbon. By this means the carbon is firmly clamped and rigidly secured to the carrier, while by loosening slightly the screw S the carbon may be turned or adjusted to any angle within reasonable limits, which is often necessary in order to bring the points of the two carbons together. The principal advantages of this construction are that the clamps may be cast at slight expense, and while securing all the advantages of the ordinary ball-and-socket joints they possess the additional recommendation of making with the end of the carbon pencil a perfect electrical contact—a thing which, with

the greater portion of the holders as heretofore made, is attained only with great difficulty.

The lower carbon-holder (illustrated in the remaining figures) is composed of the two parts e and f, which are drawn together and clamped to the cross-bar B of the lamp-frame by the screw h and nut n. The main portion consists of a semi-cylindrical socket, f, provided with two legs, l l', and terminating in the screw h. The other portion is composed of a semi-cylindrical body, e, from which projects a leg, l'', and a notched arm, g, adapted to hook under pins c, suitably situated on the sides of the socket f, as shown in Fig. 2.

The portion of the cross-bar to which the holder is clamped is either concave or convex, as shown at m, Figs. 5 and 2, in order to afford greater facility in shifting the position of the holder when it becomes necessary to adjust the carbons or to set them at different angles.

When the two portions of the holder e and f are caused to engage the end of a carbon inserted between them and the nut n tightened, the pins c depress the notched arms g, causing the upper portion, e, to bind the carbon pencil in the socket and clamping both parts of the holder firmly down to the cross-bar B of the frame.

The holder is easily taken apart when it is necessary to clean it, and, from the facility with which it is adjusted and the perfect contact it secures, forms a convenient and valuable accessory in a lamp.

I am aware that a ball-and-socket attachment for the upper carbon of an electrical lamp is not broadly new, and I am also aware that lower carbon sockets or holders have been made by which a lateral adjustment of the carbons was possible. Such therefore I do not claim; but

What I desire to secure by Letters Patent is—

1. The combination, with the carbon-supporting rod A, of a carbon holder or socket consisting of the two clamping-sections d and b and screw S, the said sections being formed with a socket at one end adapted to fit the spherical end of the rod A and grooves at the other for clamping the end of the carbon, as described.

2. The combination, in a carbon-holder, of the semi-cylindrical socket *e* and clamping-section *f*, hinged together by the arms *g* and pins *c*, and clamped to the cross-bar *B* by means of nut *n* and screw *h* passing through the bar, as described.

3. The combination, in an electric lamp, of a carbon-holder, with a cross-bar having a convex or concave seat on which the holder is clamped by means of a nut and screw, whereby the holder is capable of both lateral and angular adjustment, as described.

4. The combination of the semi cylindrical socket *f*, having legs *l* *l'*, with clamping-piece

e, having a leg, *l''*, and notched projecting arms *g*, for engaging with pins on the socket *e*, these parts being clamped together and secured to the cross-bar of an electric lamp by means of a nut, *n*, and screw *h*, attached to or forming a part of the socket *f*, substantially as shown and described.

In testimony whereof I have hereunto set my hand.

ADDISON G. WATERHOUSE.
